NOZZLE ATTACHMENT FOR POWDER
FILLING MACHINES

Charles J. Westin, Philadelphia, Pa., assignor to
F. J. Stokes Machine Company, Philadelphia,
Pa., a corporation of Pennsylvania

Application April 30, 1932, Serial No. 608,432

10 Claims. (Cl. 226—116)

This invention relates to improvement in machinery for filling cans, cartons, containers, or receptacles, with free-flowing material such as granulated sugar, salts, seeds, etc.

5 This attachment also embodies means for eliminating or removing the objectionable dust carried off by the air when this is being expelled from the container by the material.

For a further exposition of my invention reference may be had to the annexed drawing and 10 specifications at the end whereof my invention will be specifically pointed out and claimed.

In the drawing,

Figure 1 is a vertical cross section through my 15 device with parts shown in cross section.

Figure 2 is an end view of parts of my device.

Figure 3 is a vertical cross section of a portion 20 of a modified form with parts broken away.

The attachment consists of a nozzle or pipe 1 fastened to a flange 2, which is held to the hopper holding the material by means of holder 15. The nozzle or pipe 1 has at its lower end the outer peripheral edge beveled off, leaving an unbeveled portion on the bottom of the nozzle, against 25 which unbeveled portion the valve seat can seat firmly over a distance of appreciable width. The beveled portion guards against the clinging of material or dust to the end of the nozzle 1, which material or dust will prevent the proper closing 30 of valve 6, hereinafter referred to. On the lower end of the nozzle is attached a collar 5 which has provisions or holes made in it to permit the guide pins 3, which are fastened to valve 6, to extend up through this collar so that the compression 35 springs 4 may be allowed to rest on collar 5 supporting the valve by means of the washers and cotter pins at the top of guide pins 3. Valve 6 is held by means of the springs 4 against the bottom edge of the nozzle when no material is being 40 discharged. This valve has a small hole in the center shown at 11 which hole cooperates with the clean-off spud 10 to prevent packing of some kinds of material beneath the clean-off spud 10 in a ball or pile. This clean-off spud 10 is an 45 extension of the auger 9 and can be made of any non-circular form so that when it revolves it throws the material away from under the center of the auger and prevents the material from packing at this point and interfering with the free 50 closing of the valve 6. The auger is held by a collar 16 to the operating shaft which shaft is driven intermittently by the mechanism of the shaft. When the auger is put in motion it draws on the supply from the hopper above forcing the 55 material down against the valve 6 which yields

to this pressure and allows the desired quantity of material to be discharged. Spud 10 revolving with the auger prevents material packing between the auger and valve 6 and therefore allows the valve to close preventing drip, instantly the auger 60 stops.

This method of controlling the flow is very simple but has been found in actual practice to be surprisingly accurate in regulating the amount 65 of powder discharged by the machine.

When machines are operated at a high rate of speed, material is fed so rapidly that dust or float is created by the air rushing from the container. To prevent this escape of dust suction hood 13 is provided, having an air exhaust connection 19, 70 which can be attached to any suitable exhaust system and the dust collected. To make this more effective a felt pad 7 may be fastened to the bottom of the suction hood 13 as shown. Exhausing the air in this manner not only removes 75 the objectionable dust but aids in evacuating the can, thus increasing the speed at which a container may be filled. The opening between the felt ring 7 and the outer wall on suction ring 13 may be, and sometimes is, closed by the size of 80 the container to be filled. The suction is then connected to the inside of the container being filled by means of perforations 44 formed on an angle from the vacuum chamber above the felt ring 7 in a direction toward the center or outer 85 rim 8.

Where containers have very small openings a funnel 14 is provided which permits the use of a larger diameter of auger relative to the opening of the container. This accelerates the speed at 90 which such small mouth containers can be filled and adds greatly to the capacity of the machine. Funnel 14 has a flange 17 on it which carries a pad 18 for making a tight seal between the funnel and the container to be filled.

I do not intend to be limited in the practice of my invention save as the scope of the prior art and of the attached claims may require.

I claim:

1. In a filling machine, a nozzle, an auger for 100 conveying material in said nozzle, a non-circular clean-off spud at the outlet end of said auger, and a valve adjacent said spud for closing the outlet end of said nozzle, said spud co-operating with said valve to transfer material from the center 105 to the edge of said valve.

2. In a filling machine, a nozzle, an auger for conveying material in said nozzle, a non-circular clean-off spud mounted at the outlet end of said auger, a valve adjacent said spud for closing the 110

- end of said nozzle, said spud co-operating with said valve to transfer material from the center to the edge of said valve, and means for yieldingly urging said valve to closed position.
5. 3. In a machine of the type described, an auger for conveying material, a non-circular clean-off spud mounted at the outlet end of said auger, a nozzle surrounding and cooperating with said auger, a valve adjacent said spud for closing the outlet end of said nozzle, said spud co-operating with said valve to transfer material from the center to the edge of said valve, and means for guiding said valve with reciprocating motion relative to said nozzle.
10. 10. In a machine of the type described, an auger for conveying material through said nozzle, a non-circular clean-off spud mounted on said auger, and a valve adjacent said spud for closing the outlet end of said nozzle, said valve having a hole therein beneath said spud and said spud co-operating with said valve to transfer material from the center to the edge of said valve.
15. 4. In a filling machine, a nozzle, an auger for conveying material through said nozzle, a non-circular clean-off spud mounted on the outlet end of said auger, a valve adjacent said spud mounted for reciprocating motion for closing the outlet end of said nozzle, said spud co-operating with said valve to transfer material from the center to the edge of said valve.
20. 5. In a filling machine, a nozzle, an auger located in and slightly spaced from the walls of said nozzle for conveying material therein, a non-circular clean-off spud mounted on the outlet end of said auger, a valve adjacent said spud mounted for reciprocating motion for closing the outlet end of said nozzle, said spud co-operating with said valve to transfer material from the center to the edge of said valve, and a connection for exhausting air adjacent the outlet end of said nozzle beneath said valve.
25. 6. In a filling machine, a nozzle, an auger for conveying material through said nozzle, a non-circular clean-off spud at the outlet end of said auger, a valve adjacent said spud for closing the outlet end of said nozzle, said spud co-operating with said valve to transfer material from the center to the edge of said valve, and means for providing a tight joint between a receptacle to be
7. In a filling machine, a nozzle, means for feeding material through said nozzle, irregular shaped means attached to said first-mentioned means for forcing said material away from the central part of the outlet end of said nozzle, and means contacting with said second-mentioned means in closed position for controlling the flow of material from the outlet end of said nozzle.
8. In a filling machine, a nozzle having a beveled portion and an unbeveled portion at its outlet end, an auger mounted in said nozzle for conveying material therein, a non-circular clean-off spud mounted at the outlet end of said auger, and a valve adjacent said spud co-operating with the unbeveled portion of the outlet end of said nozzle, said spud co-operating with said valve to transfer material from the center to the edge of said valve.
9. In a filling machine, a nozzle, an auger for conveying material in said nozzle, a non-circular clean-off spud mounted at the outlet end of said auger, a valve adjacent said spud controlling the outlet end of said nozzle, said spud co-operating with said valve to transfer material from the center to the edge of said valve, and means for providing a tight joint between said nozzle and a receptacle to be filled.
10. 10. In a filling machine, a nozzle having its axis vertical, means in said nozzle for feeding material therethrough, irregular shaped means attached to the lowest end of said first-mentioned means for forcing material away from the central part of the outlet end of said nozzle, and means mounted at the lowest end of said nozzle and contacting with said second-mentioned means in closed position for controlling the flow of material from the outlet end of said nozzle.
